CLAIM

I claim the ornamental design for a combined laptop and desk for a child, as shown and described.

DESCRIPTION

FIG. 1 is a perspective view of the present invention, a partially opened combined laptop and desk for a child;

FIG. 2 is a perspective and fully opened view of the present invention;

FIG. 3 is a left side view of the present invention with the laptop in its closed position; the right side being a mirror image thereof;

FIG. 4 is a left side and perspective view of the present invention in its closed position.

FIG. 5 is a front, perspective view of the present invention in its closed position.

FIG. 6 is right side and perspective view of the present invention in its closed position; and,

FIG. 7 is a top plan view of the present invention in its closed position.

The broken lines represent portions of the design that form no part of the claim.
